UNITED STATES PATENT OFFICE

OTTO A. BOESEL, OF ANSONIA, CONNECTICUT, ASSIGNOR TO THE H. A. MATTHEWS MANUFACTURING COMPANY, OF SEYMOUR, CONNECTICUT, A CORPORATION

DESIGN FOR A LUGGAGE LOCK

Application filed October 23, 1930. Serial No. 37,360. Term of patent 3½ years.

To all whom it may concern:

Be it known that I, Otto A. Boesel, a citizen of the United States, residing at Ansonia, in the county of New Haven and State of Connecticut, have invented a new, original, and ornamental Design for a Luggage Lock, of which the following is a specification, reference being had to the accompanying drawing, forming part thereof.

Fig. 1 is a face view of a luggage lock showing my new design; and

Fig. 2 is a side view of the same.

I claim:

The ornamental design for a luggage lock as shown.

OTTO A. BOESEL.
